UNITED STATES PATENT OFFICE.

HAROLD W. SHONNARD, OF EAST ORANGE, NEW JERSEY.

HEAT-ENGINE.

1,072,180.

Specification of Letters Patent.

Patented Sept. 2, 1913.

Original application filed September 28, 1911, Serial No. 651,882. Divided and this application filed February 5, 1912. Serial No. 675,685.

To all whom it may concern:

Be it known that I, HAROLD W. SHONNARD, a citizen of the United States, residing at East Orange, in the county of Essex and 5 State of New Jersey, have invented certain new and useful Improvements in Heat-Engines; and I do hereby declare the following to be a full, clear, and exact description of the invention, such as will enable others 10 skilled in the art to which it appertains to make and use the same.

The present invention is a division of an application for U. S. Patent filed by me on September 28th, 1911, Serial Number 651,882 15 and relates particularly to a form of internal combustion engine therein shown and described wherein the explosive mixture is supplied in a highly heated condition to the cylinders.

20 My invention provides a simple and perfect solution of this difficulty together with an efficient lubricating means.

Certain exemplifying embodiments of my 25 invention are illustrated in the accompanying drawings wherein—

Figure 1 is an elevation of my engine, one cylinder being shown in section, Fig. 2 is a sectional view of one fuel inlet valve, Fig. 3 is a cross section of that portion of 30 a torpedo in which the engine is located, Fig. 4 is a partial elevation of the engine showing two valves in section, Fig. 5 is a sectional diagrammatic view of the preferred air and fuel supply and the lubricating 35 means, and Fig. 6 shows a modified form of valve embodying the advantages of my oil-pressure packing.

While I have shown my engine as constructed for use in submarine torpedoes 40 wherein it has great advantages, I do not limit myself to any particular use for the engine. Neither do I limit myself to the use of my improvement in engines to which the mixture is supplied at a very high temperature, as my improvements are applicable 45 in many forms of engine using mixtures supplied at ordinary temperatures.

The torpedo shell is shown at 20 and the engine is located within said shell between 50 two bulkheads 21 and 22, as shown in Fig. 3. That portion of the shell 20 which surrounds the engine is provided with openings 23, whereby the water has access to all of the exterior of the engine, thus providing

the most efficient possible cooling agent. 55 While those parts of the engine which require cooling are thus enveloped in sea water, the delicate electrical sparking mechanism is efficiently protected from the effect of contact with water by being inclosed behind the rear bulkhead 21. This sparking mechanism is shown in Fig. 3; the plugs at 24, and their actuating rods at 25. These are operated by cams 26 and are of a well known construction requiring no further description. 65

The crank attachment for the main shaft may be of any desired construction and preferably comprises a sleeve 27 running on ball bearings 28 and appropriately connected to 70 the propeller or other driven structure. The two ends of the sleeve 27 are connected by a crank pin 29 driven by connecting rods 30 whose detailed novel structure is shown in my aforesaid application for patent, and 75 is not claimed herein. It needs no further description here.

The engine cylinders, preferably four in number, are shown at 31, and the pistons at 32 are secured to the outer ends of the connecting rods 30 by special novel means illustrated in my aforesaid patent application, and not herein claimed. As shown in Fig. 3, the connecting rods and crank pin move within an inclosed crank case, and this 80 enclosure is supplied in a well known manner with oil, the movements of the crank and rods serving to throw the oil into contact with all moving parts. 85

With each cylinder 31 there are associated 90 three valves, when the engine is to be used as an internal explosion engine. These are the air inlet valve 33, the fuel inlet valve 34, and the exhaust valve 35. Where the engine is used with heated compressed air 95 alone, without internal combustion the valve 34 may be omitted. Such a mode of construction and method of operation are within my broad invention.

The preferred construction of the air inlet 100 valve is shown in Fig. 4. The valve stem 36 carries two packings 37, 38 and a valve head 39 whereby the main valve chamber is divided into compartments 40, 41, normally closed. The compressed air or equivalent 105 gas is admitted to the chamber 40 just under the valve head 39 through the passage 42, and oil is admitted to the chamber 41 by

the passage 43. Appropriate means are employed for supplying the oil under pressure tending to prevent escape of air past the packing 37. This oil pressure may be 5 somewhat greater or somewhat less than the air pressure, but in the preferred arrangement hereinafter set forth I have described a simple means for insuring equal pressure of oil and air. As the area of the packing 37 is greater than that of 39, the latter is 10 normally held to its seat, and this tendency is reinforced and is preserved even when the air pressure is not supplied to the engine, by the superiority of the area of the packing 38 over 37, and the pressure of the oil 15 within the space between them. The opening of each air valve at the proper moment is accomplished in a well known manner by a cam 44 acting upon the roller-foot 45. 20 It will be seen that, by this arrangement of the air-admission valve, I am able to completely solve the problems presented by the necessity of extremely rapid, accurate and complete control of an intensely hot gas 25 under high pressure. The packings 37 and 38 are carefully fitted to avoid leakage so far as possible, but they would be quite inadequate were it not for the presence of the oil in the chamber 41, whose pressure 30 counteracts that of the air and confines the latter within the chamber 40, save when liberated into the cylinder each time that the valve head 39 is lifted. There will, of course, exist a slow leakage of oil outward 35 past the packing 38, but since the valve body opens directly into the crank chamber, this merely adds to the general body of the lubricating oil in said chamber. Thus I 40 discard the sliding valve and the spring pressed puppet valve, and am enabled to 45 successively accomplish my novel end by use of an unbalanced puppet valve normally held closed by pressure of the air itself.

The fuel-admission valve is best shown in Fig. 2. In this instance, also, I prefer to 50 use as a lubricant oil under pressure; but the fuel is supplied at a considerably higher pressure than either the air or the oil. Within the valve chamber 34 slides the stem 55 44, with the tapering head 45 which normally closes the opening through which fuel passes from the chamber 46 to the usual sprayer (not shown in detail). The liquid fuel, gasolene, alcohol or the like, enters under pressure through the pipe 47, and the oil is admitted around the stem 44 by the pipe 48. Inasmuch as it would be dangerous to run any risk of accidental escape of the fuel into the crank case, I prefer to place 60 this fuel valve altogether outside of the engine. As shown in Fig. 2, any accidental leakage of oil and fuel would take place around the stem 44 where it leaves the main chamber 34 at 49. The valve is normally held seated by a spring 50, and is raised by

a sliding stem 51, having a step 52, bearing upon a proper cam 53. The outer end of the stem 51 does not quite reach the inner end of the stem 44, when the valve is seated, and the step 52 is held down against its cam 70 by the intermediate spring 54, in the cavity 55. By this expedient the valve can seat itself perfectly, independently of absolutely exact adjustment in the relative position of the cam; and wear at the cam 53 or step 52 75 does not interfere with perfect seating.

The exhaust valve is of a well known character. It is a puppet valve 56 (Fig. 4) having a stem 57 provided with a suitable step 58 bearing upon a cam 59. It is seated 80 by the spring 60, and admits gases from each cylinder to its appropriate exhaust pipe 61, through which these gases find their way into the interior of the torpedo behind the bulkhead 21. The gases are discharged 85 thence in any well known manner.

In Fig. 5 I have shown a preferred arrangement for supply of fuel, air and oil, in connection with certain associated apparatus used in torpedoes. It is to be understood that the relative positions of the parts shown are not essential, and that my present invention is not limited to use of the engine with special torpedo apparatus. The usual compressed air flask is shown at 62, 90 the contents thereof passing through the usual valve 63 and the pipe 64. The liquid and volatile fuel is stored in the tank 65, whence it is delivered to the admission valves 34 by the pipe 66. The position of the usual starting valve is indicated at 67, and this communicates in a well known manner by the pipe 68 with the regulating valve 69. The pipe 70 conveys the very highly compressed air charged within 62, from 63 95 to 67. The air admitted through the regulating valve 69 to the chamber 71 is at a 100 very considerable pressure, inferior however to that of the air in the flask 62. This high pressure is somewhat cut down when the engine is running by the perforated disk 72, through which the air is admitted to the engine by a large pipe 73. By this means the pipe 74, which connects the space above the liquid fuel directly with the pressure chamber 71, causes the fuel to be delivered 110 through the pipe 66 at a higher pressure than the air. The oil for lubrication and for packing of the air-admission valves is stored in the vessel 75, and delivered 115 through the oil supply-pipe 76. A pressure equal to that of the actual air supply is communicated to this oil by means of the pipe 77, connecting the top of the vessel 75 with the large pipe 73. Other means may 120 be used for creating the oil pressure and, as before stated, this pressure need not be the same as that under which the air is supplied. Where desired, superheating of the air delivered through the pipe 73 is accom- 125 130

plished by appropriate apparatus hitherto used in torpedoes in connection with the turbine engines employed for driving them.

While I have shown an arrangement whereby the highly heated air is carbureted after admission to the cylinders, it is to be understood that it is within the scope of my invention to combine the volatile fuel with the air before admission of the mixture.

10 The special valve construction which I have described makes it feasible to use very high initial temperatures and thus obtain a great increase in the horse power of an engine of a given size.

15 It is to be understood that in my claims the expression "air" covers any gas fit to be raised to a high temperature and chemically united with the fuel within the engine.

20 Various modifications may be made in my structure without departing from my invention, and I do not limit myself to the details herein shown and described.

What I claim is—

1. A heat engine having a suitable packed 25 automatic valve and external means for supplying oil under pressure to the packing of said valve, substantially as described.

2. A heat engine having an admission valve for supplying fluid thereto, a packing 30 on said valve, external means for supplying oil to said packing and means for supplying air pressure to said oil, substantially as described.

3. In a heat engine, a valve chamber and 35 valve seat, a valve stem carrying a head and two separated packings, means for supplying fluid under pressure to the space between said head and the nearer packing, and means for supplying oil under pressure to 40 the space between said packings, substantially as described.

4. In a heat engine, a valve chamber and a valve seat, a valve stem carrying a head and two separated packings having each a 45 greater area than that exposed by the valve head when on its seat, means for supplying fluid under pressure to the space between said head and the nearer packing, and means for supplying oil under pressure to the space 50 between said packings, substantially as described.

5. In a heat engine, a valve chamber and

valve seat, a valve stem carrying a head and two separated packings, the nearer packing having an area superior to that exposed by 55 the head when on its seat, and the farther packing having a still greater area, means for supplying fluid under pressure to the space between said head and the nearer packing, and means for supplying oil under 60 pressure to the space between said packings, substantially as described.

6. In a heat engine having cylinders, pistons and a crank case, a valve chamber opening into said crank case and provided 65 with a valve seat, a valve stem carrying a head and two separated packings, the farther one of which normally closes the opening into the crank case, means for supplying fluid under pressure to the space between 70 said head and the nearer packing, and means for supplying oil under pressure to the space between said packings, substantially as described.

7. In a heat engine having a cylinder, a 75 piston, and a crank shaft, a cam on said shaft, a puppet valve operated by said cam and having a stem carrying a valve head and two separated packings, means for supplying fluid under pressure immediately behind 80 said valve head and means for supplying oil under pressure between said packings, substantially as described.

8. In a heat engine, a valve chamber having a seat and two side openings thereto, a 85 valve stem within said chamber carrying a head adapted to fit upon said seat, a packing between said side openings and a third packing beyond the other side opening, said packings having each an area greater than 90 that exposed by the valve head when seated; in combination with a reservoir of compressed air connected to the side opening next beneath the valve head, an oil tank connected with the other side opening and 95 means for admitting compressed air from said reservoir to said oil tank, substantially as described.

In testimony whereof, I affix my signature, in presence of two witnesses.

HAROLD W. SHONNARD.
